W. E. RIECKEN,
WINDING MACHINE,
APPLICATION FILED DEC. 6, 1918.

1,381,933.

Patented June 21, 1921.

Inventor:
William E. Riecken
by *J. G. Roberts*
Att'y.

UNITED STATES PATENT OFFICE.

WILLIAM E. RIECKEN, OF GLENDALE, NEW YORK, ASSIGNOR TO WESTERN ELECTRIC COMPANY, INCORPORATED, OF NEW YORK, N. Y., A CORPORATION OF NEW YORK.

WINDING-MACHINE.

1,381,933.

Specification of Letters Patent. Patented June 21, 1921.

Application filed December 6, 1918. Serial No. 265,592.

To all whom it may concern:

Be it known that I, WILLIAM E. RIECKEN, a citizen of the United States, residing at Glendale, in the county of Queens, State of New York, have invented certain new and useful Improvements in Winding-Machines, of which the following is a full, clear, concise, and exact description.

This invention relates to a winding machine and more particularly to a serving head for spirally applying ribbon or tape to a continuous thread core. The invention will perhaps find its widest application in connection with machines for applying tinsel tape to a core to form an electrical conductor used in telephone switchboard cords and other similar compound electrical conductors.

The object of this invention is to provide a serving head for forming such tinsel conductors which may be operated at high speed without causing the frequent breakage of the tinsel tape which is incident to the operation of certain serving heads heretofore used when operated at high speeds.

In order to attain this object in accordance with a feature of the invention, the frictional engagement of a braking means with the spool carrying member is controlled directly and solely by the tension of the serving material as it is unwound from the spool so that the extent of such engagement varies in response to variations in the tension.

This and other features of the invention, not specifically mentioned above, will clearly appear from the following description and the annexed drawing which shows a perspective of a serving head constructed in accordance with the invention.

In the drawing, 1 represents a hollow spindle or shaft which may be suitably supported in bearings at 2, not shown, and rotated at high speed by some suitable source of power, also not shown. Extending longitudinally through the shaft 1 is a thread core 3 delivered from a reel or other suitable means, not shown, to the serving head and drawn therethrough at a definite rate by other suitable means, also not shown. A light weight spool 4 from which the tape or other serving material is unwound is loosely mounted on the spindle 1 by means of the sleeve 6 having a flange 7. Rigidly fastened to the spindle 1 by means of a set screw or in some other suitable manner is a plate

member 8 to which a stud 9 is attached by means of threaded portions engaging the plate member 8 and a nut 10. Another diametrically oppositely placed balancing arm 11 is attached to the plate member 8 in a similar manner. Also attached to the plate member 8 by means of a screw 12 engaging one end thereof is a spring member 13, a portion 14 of which is adapted to be in engagement with an adjusting nut 15 threaded on the stud 9, while a flat portion 16 of the spring member is adapted to frictionally engage the inner surface of the flange 7 of the sleeve 6. The free end of the spring 13 is formed to provide a looped portion 17 through which the serving material 5 is guided from the spool 4 after passing over the arm 9. By means of the adjusting nut 15, the pressure of flexible portion 16 against the flange 7 may be adjusted to any desired value so that the tension of the serving material 5 passing through the guiding portion 17 will correctly regulate such pressure during the operation of the serving head.

In case the tension is increased, portion 16 is gradually removed from the flange 7 thereby reducing the length of the line of contact between the brake and the flange while a reduction in the tension increases the extent of such contact.

What is claimed is:

1. In a serving head, a spool for the serving material, a frictional brake with a flexible bearing portion for controlling the spool, and means controlled by the serving material for gradually varying the extent of contact of the brake.

2. In a serving head, a spool-carrying means, a spool for the serving material mounted thereon, guiding means for the serving material, a spring brake with a flexible bearing portion frictionally engaging the spool-carrying means, and means automatically controlled by the guiding means for gradually varying the extent and pressure of the contact between the brake and the spool-carrying means.

3. In a serving head, a rotatable spindle, a flanged sleeve loosely mounted thereon, a spool mounted on the sleeve for the serving material, a wire spring brake member with a flexible bearing portion in contact with the inner surface of the flange, and means for adjusting the pressure exerted by the brake member against the flange, a free portion of

the brake member being provided with guiding means for the serving material and responding to variations in tension of such material to vary the extent of contact between the brake and the flange.

4. In a serving head, a rotatable spindle, a flanged sleeve loosely mounted thereon, a spool mounted on the sleeve for the serving material, a brake member having a flexible bearing portion for frictionally engaging the flange with a line contact, and means controlled by the serving material for varying the length of the contact line.

5. In a serving head, a rotatable spindle, a flanged sleeve loosely mounted thereon, a spool mounted on the sleeve for the serving material, a wire spring brake member having a flexible bearing portion for frictionally engaging the flange, means for adjusting the pressure exerted by the brake member against the flange and a loop in said

wire spring brake member through which the serving material passes to automatically vary the brake tension.

6. In a serving head, a rotatable spindle, a flanged sleeve loosely mounted thereon, a spool mounted on the sleeve for the serving material, a wire spring brake member having a flexible bearing portion for frictionally engaging the flange, said brake member being provided with guiding means for the serving material responsive to variations in the tension of such material, means for adjusting the normal pressure exerted by the brake member against the flange, and means to direct the serving material from the spool to the guiding means in the said brake member.

In witness whereof, I hereunto subscribe my name this 5th day of December A. D., 1918.

WILLIAM E. RIECKEN.
